BOAT

Albert B. Borgstrom, 1441 Olive Ave., Chicago, Ill.

Filed July 24, 1962, Ser. No. 71,029

Term of patent 14 years

(Cl. D71—1)

The dominant features of the design reside in the portions shown in full lines.

I claim:

The ornamental design for a boat, substantially as shown and described.
